UNITED STATES PATENT OFFICE

105,606

DESIGN FOR A SURFACE BURIAL VAULT OR ARTICLE OF SIMILAR NATURE

Claude R. Neff, Camden, Ohio, assignor to The
Neff & Fry Company, Camden, Ohio, a corpo-
ration of Ohio

Application March 5, 1937, Serial No. 68,035

Term of patent 14 years

To all whom it may concern:

Be it known that I, Claude R. Neff, a citizen
of the United States of America, residing at
Camden, in the county of Preble and State of
Ohio, have invented a new, original, and orna-
mental Design for a Surface Burial Vault or
Article of Similar Nature, of which the following
is the specification, reference being had to the
accompanying drawing, forming a part thereof:

Figure 1 is a perspective view of a surface
burial vault, showing my new design.

Figure 2 is a plan view of the vault shown in
Figure 1.

I claim:

The ornamental design for a surface burial
vault or article of similar nature, as shown.

CLAUDE R. NEFF.
